UNITED STATES PATENT OFFICE.

EMANUEL PATENAUME AND SAMUEL P. PATENAUME, OF KORBEL, CALIFORNIA.

SASH-FASTENER.

988,655.

Specification of Letters Patent.

Patented Apr. 4, 1911.

Application filed February 14, 1911. Serial No. 608,499.

To all whom it may concern:

Be it known that we, EMANUEL PATE-
NAUME and SAMUEL P. PATENAUME, citizens
of the United States, residing at Korbel,
5 in the county of Humboldt, State of California,
have invented a new and useful
Sash-Fastener, of which the following is
a specification.

It is the object of the present invention to
10 provide an improved sash fastener arranged
to hold the sashes of a window at substan-
tially any desired elevation, which fastener
will not be exposed prominently to view
15 from outside the window and may not be
reached except from within.

One aim of the present invention is to pro-
vide means whereby the fastener may be
held inoperative for any desired length of
time so as to permit free raising and lower-
20 ing of the window sashes.

A further aim of the invention is to pro-
vide a fastener for this purpose so con-
structed that it may be placed upon the mar-
ket and readily applied by anyone to any
25 ordinary window frame with but little alter-
ation of the frame and the sashes.

In the accompanying drawings—Figure 1
is a view in front elevation of a window to
which the fastener is applied. Fig. 2 is a
30 view in side elevation of the device mounted
upon one stile of the window frame. Fig.
3 is a vertical sectional view on the line
3—3 looking in the direction indicated by
the arrows, in Fig. 2 of the drawings. Fig.
35 4 is a rear elevation of the device removed
from the window frame. Fig. 5 is a verti-
cal sectional view on the line 5—5 of Fig.
4 looking in the direction indicated by the
arrows. Fig. 6 is a detailed perspective view
40 of a portion of one of the window sashes.

In the drawings, the device is illustrated
as including, in its structure, a base plate 10.
Mounted for rocking movement upon one
5 face of the plate 10 is a shaft 11 and a shaft
12. Springs 13 and 14 are arranged upon
these shafts respectively and normally hold
them rocked in one direction. Arms 15 and
16 are secured to the shafts 11 and 12 re-
50 spectively at corresponding ends, the shafts
being located one above the other, and these
arms, at their upper ends, have pivotal con-
nection as at 17 with finger buttons 18 and
19 respectively. These finger buttons 18 and
55 19 are slidably mounted through the plate
10 as is clearly shown in Fig. 5 of the draw-
ings and, for a purpose to be presently ex-

plained, each of the said buttons is formed
in its free extremity with a notch 20.

It will be observed from an inspection of
Figs. 4 and 5 of the drawings, that the 60
springs 13 and 14 serve to hold their re-
spective shafts 11 and 12 normally in a po-
sition to project the finger buttons 18 and
19 beyond the outer face of the plate to the
maximum degree. It will however be fur-
65 ther understood that either of these but-
tons may be pressed to rock its respective
shaft against the tension of the respective
spring. At the other end of each shaft 11
and 12, there is fixed an upstanding arm, in
70 the case of the shaft 11, indicated by the
numeral 21, and in the case of the shaft 12,
indicated by the numeral 22.

Sleeves 23 and 24 are secured upon and
project from the rear face of the plate 10
75 and in their under sides are slotted as at 25.
The upper ends of the arms 21 and 22 pro-
ject through the slots in the respective sleeves
23 and 24 and engage in seats in the under
sides of bolts indicated one by the numeral 80
26 and the other by the numeral 27. Nor-
mally, the shafts 11 and 12 are held by the
springs in such position as to project the
bolts 26 and 27 beyond the forward face of
the plate 10 in the manner illustrated in
85 Figs. 3 and 5 of the drawings.

From the foregoing it will be understood,
that by pressing upon the finger button 18,
the bolt 26 will be retracted or slid rear-
wardly in the sleeve 23, and on the other 90
hand, by similarly manipulating the finger
button 19, the bolt 27 will be retracted.
These bolts 26 and 27 are located in different
vertical planes so that one of them will co-
operate with the lower sash and the other 95
one with the upper sash.

It will be observed from an inspection of
Fig. 1 of the drawings that the device above
described is applied to one stile of the win-
dow frame indicated by the reference char-
acter F and by referring to Fig. 6 it will be
observed that the corresponding or adjacent
5 stile of each window sash (indicated by the
reference character S), is formed with sock-
ets 28 to receive the projecting ends of the 100
respective bolts 26 and 27. When so en-
gaged, the bolts hold the respective sashes
against up or down movement although such
movement of either sash may be accom-
plished by first pressing against the proper 105
finger button and then moving the sash as
desired.

When the sashes F are completely closed, they will be so held by the bolts 26 and 27 of the device. However, during the day time, it is desirable that the sashes may be 5 freely raised or lowered without the necessity of manipulating the finger buttons 18 and 19 and, also, where the sashes are very heavy or not properly balanced or where they have become swollen in the frame and 10 are difficult to move, it is desirable that the buttons be held depressed or that the device be rendered inoperative in some other suitable manner. Preferably, this is accomplished by the provision of detents engageable one with each of the buttons when the 15 same are in position to render the respective bolts inoperative. Each of these detents consists of an arm 29 which is mounted for rocking movement upon a face plate 30 through which the buttons 18 and 19 project. Each arm has a laterally projecting 20 end portion 31 which is adapted to be engaged in the notch 20 in the respective button.

25 What is claimed is:

1. A device of the class described comprising a base plate, a rock shaft upon the plate, arms projecting from the shaft at the ends thereof, a spring upon the shaft between the 30 arms normally holding the shaft rocked in one direction, a finger button connected with one arm and projecting through the plate and operable to rock the shaft against the tension of the spring, a sliding bolt also 35 projecting through the plate and actuated by movement of the other arm, and a keeper for the bolt.

2. A device of the class described comprising a base plate, a slotted sleeve projecting 40 from one face of the base plate, a rock shaft upon the plate, arms projecting from the shaft at the ends thereof, one of the said arms projecting through the slot in the sleeve, a spring upon the shaft between the

arms normally holding the shaft rocked in 4 one direction, a finger button connected with the other arm and operable to rock the shaft against the tension of the spring, a sliding bolt engaged by the first mentioned arm and movable in the sleeve to project beyond the 5 plate when the shaft is rocked against the tension of the spring, and a keeper for the bolt.

3. A device of the class described comprising a base plate, a rock shaft upon the plate, 5 arms projecting from the shaft at the ends thereof, a spring upon the shaft between the arms normally holding the shaft rocked in one direction, a sliding bolt operatively engaged by one arm and projecting through the plate, a keeper for the bolt, a finger button connected with the other arm and operable to rock the shaft against the tension of the spring, and a detent for the finger button.

4. A device of the class described comprising a base plate, a rock shaft upon the plate, arms projecting from the shaft at the ends thereof, a spring upon the shaft between the arms normally holding the shaft rocked in one direction, a sliding bolt operatively engaged by one arm and projecting through the plate, a keeper for the bolt, a finger button connected with the other arm and operable to rock the shaft against the tension of the spring, and a detent for the finger button, the said detent comprising a rocking arm having a laterally projecting portion arranged to engage in a notch in the end of finger button.

In testimony that we claim the foregoing as our own, we have hereto affixed our signatures in the presence of two witnesses.
